C. S. SMITH
MATCH SCRATCHER

Filed Feb. 23, 1922

Charles S. Smith

INVENTOR.

BY

Joseph A. Miller

ATTORNEY.

UNITED STATES PATENT OFFICE.

CHARLES S. SMITH, OF PROVIDENCE, RHODE ISLAND.

MATCH SCRATCHER.

Application filed February 23, 1922. Serial No. 538,429.

To all whom it may concern:

Be it known that I, CHARLES S. SMITH, a citizen of the United States, residing at Providence, in the county of Providence and 5 State of Rhode Island, have invented new and useful Improvements in Match Scratchers, of which the following is a specification.

This invention relates to certain new and 10 useful improvements in match scratchers and 15 pertains more particularly to an article of this kind which is formed for attachment to the clothing of the user.

The primary object of the invention is to 20 provide a match scratcher which is formed for attachment to the vest of the user and 25 which presents a neat, attractive and ornamental appearance.

A further object of the invention is to 25 provide novel means for holding the device in position.

The invention also aims to provide a match scratcher for personal wear, which is simple and economical and which is very light in weight.

25 In the drawings:

Figure 1 is a front elevation of the invention;

Figure 2 is a section on line 2—2 of Figure 1; and

30 Figure 3 is a section on line 3—3 of Figure 2.

In proceeding in accordance with the present invention, a plate of tin or other suitable thin metal, such as sheet steel is 35 employed and which is shaped to form a body 1 and a peripheral rim 2, the latter following the entire margin of the body and extending rearwardly of the front face of the body and at an incline thereto, as depicted in the drawings, whereby the beveled rim provides a hollow back for the plate-like body.

The plate-like body 1 has a series of transverse corrugations 3 formed therein, arranged in a panel-like form. The plate-like body is preferably of rectangular form, having its four corners rounded so as to enhance the ornamental appearance of the article and to also eliminate projections likely to catch 50 against the clothing, in which regard the beveled rim also serves.

The corrugations are of the usual concavo-convex type being formed by pressing the metal of the body so that each side face 55 thereof is similarly equipped with corruga-

tions. In order to provide means for attaching the body to the clothing, a pin 4 is pivoted at 5 to the rear of the body and is engaged at its free end by a keeper 6. The pivoting means of the pin, as well as the 60 keeper, may each be soldered to the corrugations of the plate-like body, the concave parts of which corrugations serve to afford pockets to receive the solder, so that the pin parts are more effectively secured to the 65 plate-like body. The corrugations appearing on the rear face of the body 1, further act to grip the vest or other part of the clothing to which the article is affixed and in performing this function same are assisted by the free edge of the beveled rim which latter engages against the clothing and into the hollow rear face of the body provided by the outwardly extending rim. In this latter regard it will be understood 70 that the pin 4 presses the cloth against the back face of the body and also draws the cloth against the free edge of the rim of the body.

Having thus described my invention, what 80 I claim as new and desire to secure by Letters Patent is:

1. In a match scratcher, a plate-like body having transverse corrugations pressed out therefrom so as to occur on both the front 85 and rear faces of the body and having a beveled rim extending rearwardly to form clothes engaging means at its free edge, and a pin secured to the back of the body for attaching the device to the clothing of the 90 user and for forcing the clothing against the corrugations occurring on the rear face of the body.

2. In a match scratcher, a body having a series of corrugations formed to occur on 95 the front and back thereof, a rim extending outwardly from the body and formed to engage the clothing of the user and a fastener for securing the body to the clothing and for holding the latter engaged with 100 the corrugations occurring on the rear face of the body.

In testimony whereof I have signed my name to this specification in the presence of two subscribing witnesses.

CHARLES S. SMITH.
